UNITED STATES PATENT OFFICE

109,567

DESIGN FOR A CURTAIN OR SIMILAR ARTICLE

Herman H. Newberger, Chicago, Ill.

Application January 19, 1938, Serial No. 74,418

Term of patent 7 years

To all whom it may concern:

Be it known that I, Herman H. Newberger, a citizen of the United States, residing at Chicago, county of Cook, and State of Illinois, have invented a new, original, and ornamental Design for a Curtain or Similar Article, of which the following is a specification, reference being had to the accompanying drawing, forming a part thereof, in which:

Figure 1 is a front view in elevation of a curtain or similar article showing my new design; and Fig. 2, a transverse sectional view.

I claim:

The ornamental design for a curtain or similar article, as shown.

HERMAN H. NEWBERGER.
